J. C. SNELL

POTENTIOMETER

Filed Feb. 4, 1924

Inventor
James S. Snell
By, Fred G. Ladd Atty.

UNITED STATES PATENT OFFICE.

JAMES C. SNELL, OF OAK PARK, ILLINOIS, ASSIGNOR TO PREMIER ELECTRIC COMPANY, OF CHICAGO, ILLINOIS, A CORPORATION OF ILLINOIS.

POTENTIOMETER.

Application filed February 4, 1924. Serial No. 690,389.

The invention relates to potentiometers and more particularly to those adapted to be used for radio service.

The object of the invention is to provide a potentiometer with means whereby the circuit between the "A" and "B" batteries may be broken, thus breaking the plate voltage and insuring the filaments of the tubes against accidental rupture. Another object 10 of the invention is to provide a potentiometer with an automatic cut-out or disconnector which will break the shunt circuit between the positive and negative terminals of the "A" battery caused when the main circuit 15 between the "A" and "B" batteries is broken, thereby preventing a drain on the "A" battery. Still another object of the invention is to provide improvised means for holding a switch arm against a resistance coil in 20 which provision is made for removing the switch arm when desired.

The invention consists in the several novel features hereinafter set forth and more particularly defined by claims at the conclusion 25 hereof.

In the drawings: Fig. 1 is a rear view of a potentiometer embodying the invention. Fig. 2 is a front view. Fig. 3 is a section on line 3—3 of Fig. 2. Figs. 4 and 5 are detail 30 views of the automatic cut-out or disconnector. Fig. 6 is a diagrammatic view of the improved potentiometer applied to the plate circuit of a radio receiving system.

The invention is exemplified in a potentiometer for the plate circuit of a radio receiving system which comprises an "A" battery 7 connected by conductors 8 and 9 to the filament of an electron tube 10, a pair of phones 12 connected by conductor 11 to the plate of the tube, a "B" battery 13 connected to the phones 12 by a conductor 14 and a potentiometer 15 disposed between the "A" and "B" batteries, to regulate the voltage and the amount of plate current passing through 40 the conductor 8 and the tube 10.

The potentiometer comprises a circular insulated base 20, a sleeve 22 extending through the center of the base 20, and a dial 23 secured on the sleeve by a nut 27, and adapted 50 to be positioned against the panel of the usual radio apparatus container. A shaft

28 with an integral switch arm 29 at one end thereof extends through the sleeve 22, and at the opposite end adjacent the dial a pointer 30 and a handle 31 are secured to the shaft 55 by a screw 32.

An insulated core 34 is disposed in a circular slot 33 in the base 20. A resistance coil 35 of suitable ribbon or wire is wound around core 34 and is adapted to be engaged 60 by the switch arm 29 as it rotates with the shaft 28, when manually operated to control the direction and the amount of current passing through the resistance coil. One end of wire-coil 35 is connected by a screw 37 to a 65 terminal plate 36 which is secured by a screw 39 to the insulated base 20 and is adapted to receive conductor 16 from the negative terminal of the "A" battery 7. The other end of the resistance coil 35 is connected by an 70 insulated wire conductor 41 which is disposed in a slot 43 in base 20, to one end of a spring conductor 42 which is secured to the base of a screw. The spring conductor has a raised portion, adjacent one end of coil 35 75 which is adapted to engage the switch arm 29 as it passes over spring conductors 42. A flat plate 45 of conductive material is secured to the bottom of spring conductor 42 and normally engages a contact stud 46 on terminal 47 which is secured to base 20 by a 80 screw 48.

On the bottom of switch arm 29 an insulated strip 49 is secured so that when the switch arm is rotated and passes off the resistance coil 35, it will engage the raised portion of the spring conductor 42 and force it inwardly thereby causing the plate 45 to leave the contact stud 46 and break the circuit between terminals 36 and 47. 85

By allowing a space 60 on the insulated core 34 to be left at the end of the resistance coil 35, means is provided for breaking the plate circuit between the "A" and "B" batteries. 90

A terminal 50, adapted to receive the conductor from the "B" battery is disposed between the terminals 36 and 47 on the base 20 and is secured thereto by a screw 58. The upper end of terminal 50 has a hole through 100 which the shaft 28 passes. A plate 52 is rigidly secured by a stud 53 to the terminal

50 and has a hole adjacent the hole in the terminal 50 which acts as a seat for the inner end of the switch arm 29. Adjacent plate 52, a plate 55 is pivotally secured thereto by a stud 54 and is adapted to engage the outer end of switch arm 29 so as to hold shaft 28 from lateral displacement. This exemplifies means for holding switch 29 in pressed relation against the resistance coil 35. By swinging plate 55 away from the switch arm 29 and by loosening the set screw 32, the shaft 28 and switch arm 29 may be removed.

The operation of the potentiometer will be as follows. The current from the "B" battery will enter the potentiometer at terminal 50 and will be conducted through the switch arm 29 to the resistance coil 35. At this point the current will branch in two directions, part of the current flowing through the resistance coil 35 at one side of the switch arm and out by way of the terminal 39, the other portion of the current flowing through the remainder of the resistance coil 35, conductor 41, flat spring conductor 42, and terminal 47. When the circuit between the "A" and "B" batteries is to be broken, the switch arm 29 will be rotated until it leaves the resistance coil 35, as at 60. As it leaves the coil the underside of the switch arm 29 will engage the raised portion 36 of the spring conductor 42, and cause it to be forced inwardly, thereby disconnecting the plate 45 and stud 49 and breaking the shunt circuit across the positive and negative terminals of the "A" battery.

The invention exemplifies an improved potentiometer in which provision is made for disconnecting the circuit between the "A" and "B" batteries thereby insuring the tubes against accidental rupture, and in which provision is made for simultaneously breaking the shunt circuit between the positive and negative terminals of the "A" battery when the circuit between the "A" and "B" batteries is broken, thereby eliminating the drain on the "A" battery.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination with a source of electrical current, a circuit for said source of current, and a second source of electrical current, of a potentiometer comprising a resistance element connected in shunt with said circuit, a contact connected to said second source of current, said contact being movable over said resistance element to include more or less of and movable off said element, and means controlled by the con-

tact in its off position to break the circuit through the resistance element and prevent the flow of current from the first mentioned source of current through said resistance element.

2. The combination with a source of electrical current, a circuit for said source of current, and a second source of electrical current, of a potentiometer comprising a resistance element connected in shunt with said circuit, a contact connected to said second source of current, said contact being movable over said resistance element to include more or less of and movable off said element, and switch means controlled by the contact in its off position to render the circuit through the resistance element ineffective and prevent an effective flow of current from the first mentioned source of current through said resistance element.

3. The combination with a plate circuit of a radio receiving system comprising an "A" battery, a circuit for said battery, and a "B" battery, of a potentiometer comprising a resistance element connected in shunt with said circuit, a contact connected to said "B" battery, said contact being movable over said resistance element to include more or less of and movable off said element, and means controlled by the contact in its off position to open the circuit through the resistance element and prevent the flow of current from the "A" battery through said resistance element.

4. In an electrical controlling device, the combination of a supporting member, a resistance element mounted on said member, a contact member having its inner end slidably and pivotally mounted in said supporting member and its outer end movable over the resistance element to include more or less thereof, and an arm having its inner end adapted to bear against the contact member to press it against the coil and its outer end pivoted to the base to permit the arm to be rotated out of engagement with said contact member so that the latter may be removed from the base.

5. In a potentiometer, a resistance winding, a terminal plate having a permanent electrical connection to one end of said winding, a second terminal plate with a spring connection to the other end of said winding, a switch arm normally in contact with said winding, a third terminal connected electrically to said switch arm, means for operating the switch arm to disengage said arm from said winding, and means operating as an incident to the disengagement of said arm, for breaking the spring connection between said second terminal plate and said resistance winding.

6. In a potentiometer, a resistance winding, a terminal plate having a permanent electrical connection to one end of said wind-

ing, a second terminal plate with a spring connection to the other end of said winding, a switch arm normally in contact with said winding, a third terminal connected electrically to said switch arm, means for operating a switch arm to disengage said arm from said winding, and a projection on said arm for breaking the spring connection between said second terminal plate and the resistance winding, when said arm is disengaged from 10 said winding.

Signed at Chicago, Illinois this 18th day of December 1923.

JAMES C. SNELL.
